UNITED STATES PATENT OFFICE.

VALENTINE H. HALLOCK, OF QUEENS, ASSIGNOR OF ONE-HALF TO JOHN A. BEYER, OF BROOKLYN, NEW YORK.

PACKING-RING.

SPECIFICATION forming part of Letters Patent No. 242,306, dated May 31, 1881.

Application filed February 28, 1881. (No model.)

To all whom it may concern:

Be it known that I, VALENTINE H. HALLOCK, a citizen of the United States, residing at Queens, in the county of Queens and State 5 of New York, have invented new and useful Improvements in Packing-Rings, of which the following is a specification.

This invention relates to packing-rings for plungers and other like parts of machinery—as, 10 for example, the plungers used in damper-regulators, as shown and described in Letters Patent of the United States granted to me December 9, 1879, No. 222,489.

The particular class of packing-rings to which 15 my invention relates comprise a metallic internally screw-threaded and shouldered outer ring, a flanged packing-ring of leather or other similar material, resting on the shoulder of the outer ring by means of its flange, so as to hug 20 the plunger, and a metallic externally screw-threaded inner ring fitted into the outer ring, for clamping and retaining the packing-ring in its position. One of the conditions necessary to the successful working of the plunger 25 is that the bend of the packing-ring shall not be crowded against it in the angle formed by the lower end of the inner ring and the side of the plunger, and the primary object of my invention is to preserve this condition; to which 30 end it consists in the employment of an annular tapering lip or flange projecting from the lower end of the inner ring into the packing-ring and interposing itself between the bend 35 of the packing-ring and the plunger. Said annular tapering lip or flange is adjustable, and by this feature it is adapted to the purpose of regulating the area or portion of the packing-ring that comes in contact with the plunger.

This invention is illustrated in the accompanying drawings, in which Figure 1 represents 40 a vertical cross-section. Fig. 2 is a plan or top view. Fig. 3 illustrates a modification of the gage-ring.

Similar letters indicate corresponding parts.

The letter A designates the metallic outer 45 ring; B, the leather or other packing-ring; C, the metallic inner or clamping ring, and D the annular tapering lip or flange.

The outer ring, A, is provided with an in-

ternal shoulder, e, and with a screw-thread both 50 above and below the shoulder, the lower thread being a means for attaching the outer ring to the end of the cylinder containing the plunger, for which the whole constitutes a packing. Other means, however, can be used for attaching the ring A to the cylinder.

The packing-ring B is provided with a flange, f, whereby it rests on the shoulder e of the outer ring, this flange being formed by pressure, in 55 a well-known manner.

The inner ring, C, is provided with an external screw-thread, corresponding to the thread of the outer ring, and it is secured in the outer ring by that means, so as to clamp the packing-ring B and hold the same firmly in its position.

The lip or flange D tapers to a point, or nearly so, in an outer direction, and it projects from the lower end of the inner ring, C, into the packing-ring B, so as to interpose itself between the bend of the packing-ring and the 70 plunger, thus leaving only a straight portion of the packing-ring come in contact with the plunger, which insures its successful operation. In the example shown in the drawings in Figs. 1 and 2 the lip or flange D is made independent 75 from the other parts, and is secured within the inner ring, C, while in Fig. 3 it is represented as being formed in one piece with the inner ring. The position of the lower edge of the lip or flange D determines the effective 80 area of the packing-ring, only that portion thereof which is left free beyond or below such edge being permitted to come in contact with the plunger.

Now, in order to allow this area of the packing-ring to be regulated according 85 to its width, the lip or flange D is made adjustable relatively to the free edge of the packing-ring, and in this example the desired purpose is accomplished simply by securing the lip or flange D within the inner ring, C, by 90 means of a screw-thread, as shown in Figs. 1 and 2.

What I claim as new, and desire to secure by Letters Patent, is—

1. The combination of a metallic internally-threaded and shouldered outer ring for attachment to the end of a cylinder, a flanged packing-ring resting on the shoulder of the outer

ring by means of its flange, a metallic externally-threaded inner ring fitted into the outer ring, and an annular tapering lip or flange projecting from the inner ring into the packing-ring, substantially as shown and described, for the purpose set forth.

2. The combination of a metallic internally-threaded and shouldered outer ring for attachment to the end of a cylinder, a flanged packing-ring resting on the shoulder of the outer ring by means of its flange, a metallic externally-threaded inner ring fitted into the outer

ring, and an annular tapering lip or flange adjustably secured to the inner ring and projecting into the packing-ring, substantially as shown and described, for the purpose set forth.

In testimony whereof I have hereunto set my hand and seal in the presence of two subscribing witnesses.

VALENTINE H. HALLOCK. [L. S.]
